UNITED STATES PATENT OFFICE.

FREDERICK W. LINAKER, OF DUBOIS, PENNSYLVANIA.

SOOT-CLEANER.

1,318,293.

Specification of Letters Patent.

Patented Oct. 7, 1919.

Application filed May 4, 1917. Serial No. 166,352.

To all whom it may concern:

Be it known that I, FREDERICK W. LINAKER, a subject of the King of England, residing at Dubois, in the county of Clearfield 5 and State of Pennsylvania, have invented certain new and useful Improvements in Soot-Cleaners, of which the following is a specification.

This invention relates to certain new and 10 useful improvements in soot cleaners.

The present invention is particularly designed for use with boilers of the Babcock and Wilcox construction, known in the trade as the B. & W. boiler, which includes water 15 tubes slightly inclined from the horizontal and arranged in staggered relations, and includes means for diverting or dividing the jets delivered from the cleaning fluid distributing pipe, so that the oblique spaces between the tubes will be traversed by the 20 streams, as well as affording a protecting means for those portions of the upper water tubes that are in direct alinement with the discharge orifices of the cleaning fluid distributing pipes to obviate erosion of the 25 water tubes and accordingly prolong the life thereof.

With these general objects in view and others that will appear as the nature of the 30 invention is better understood, the same consists in the novel construction, combination and arrangement of parts hereinafter more fully described, illustrated in the accompanying drawings, and then claimed.

35 In the drawings forming a part of this application and in which like designating characters refer to corresponding parts throughout the several views:—

Figure 1 is a longitudinal sectional view 40 of a water tube boiler of the B. & W. type with the present invention in operative position therein.

Fig. 2 is a fragmentary detail sectional view showing the installation of one form of 45 the soot cleaner in operative position relative to the water tubes, an enlarged detail of which is shown in Fig. 5.

Fig. 3 is an enlarged detail sectional view 50 of the preferred form of water tube shield and cleaning fluid distributing pipe support, the discharge orifices of the distributing pipe being shown in staggered relation.

Fig. 4 is a sectional view taken on line 55 IV—IV of Fig. 3.

Fig. 5 is an enlarged detail sectional view

of a modified form of shield as shown in Fig. 2.

Fig. 6 is a cross-sectional view taken on line VI—VI of Fig. 5.

Fig. 7 is an enlarged detail sectional view 60 of another modified form.

Fig. 8 is a cross-sectional view taken on line VIII—VIII of Fig. 7.

Fig. 9 is still another modified enlarged 65 detail sectional view of the invention.

Fig. 10 is a cross-sectional view taken on line X—X of Fig. 9.

Figs. 11 and 12 are sectional views of different forms of distributing pipes, Fig. 11 showing the discharge nozzles or orifices in 70 alinement and Fig. 12 disclosing the same in staggered relation.

Fig. 13 is a sectional view of another modified form of the invention.

In boilers of the B. & W. type where the 75 tubes are arranged in staggered relation, the tubes of the second row being disposed directly beneath the spaces intervening the tubes of the first or upper row, difficulty has been found in employing a revolvably-mounted cleaning fluid distributing pipe 80 with discharge orifices or nozzles discharging the cleaning fluid agent in a direct radial path as the fluid will necessarily strike the tubes in the second row and after some use 85 of the cleaner, the tubes will become eroded and practically eaten away and rendered worthless at the points where the cleaning fluid agent travels in its shortest path to contact the tubes. It has heretofore been 90 impractical to clean boiler tubes of this type without having the discharge nozzles or orifices of the distributing pipe angularly disposed relative thereto so as to cause the jets of cleaning fluid to be directed obliquely 95 through the spaces between adjacent tubes. The present invention aims to overcome this difficulty by prolonging the life of the water tube as well as permitting a revolvably mounted cleaning fluid distributing pipe 100 with direct radial nozzles to be used, and still causing the jets of cleaning fluid agent to travel in oblique paths in the spaces between adjacent tubes.

Referring more in detail to the accompanying drawings, and particularly to Fig. 1, there is shown a longitudinal sectional view of a boiler designated by the numeral 15, the same being of the B. and W. type, including steam domes 16 and the water 110

2

tubes 17 slightly inclined from the horizontal as is illustrated. The supply system for the cleaning fluid distributing pipes has a pipe connection 18 with the steam dome, 5 the pipe being connected to the main line 19 supported upon brackets as is illustrated and communicating with any desired number of branch pipes 20, three of which are shown in Fig. 1, although any number may 10 be employed while suitable controlling devices and automatic air relief valves may be employed in the supply system, of any well known form, in this art.

As shown in Fig. 2, the boiler 15 has 15 journaled through one side thereof a revolvably mounted distributing pipe 21 having a sprocket wheel swivel joint 22 fixed thereto exteriorly of the wall 15 and operated in the usual manner by the chain 23. The form 20 of distributing pipe 21 shown in Fig. 2 has the discharge orifices or nozzles 24 arranged in staggered relation to provide two aligned rows thereof so that the adjacent nozzles or orifices will project streams toward each 25 other but in different paths.

As shown in Fig. 3 there is provided protecting means for the second row of water tubes 25 in the form of shields supported by said tubes 25 as well as the tubes 26 in 30 the upper row. Each shield comprises a pair of identically formed members, the separate members of each shield including a main plate 27 having the upper end thereof resting upon an upper tube 26 while the 35 lower end rests upon a tube 25 in the second row. Upstanding lugs 28 are carried by the upper ends of each of the main plates and have curved seats thereon for the reception of the cleaning fluid distributing pipe 21 40 while a strap or cover 29 is connected at its ends to the opposite sides of the lugs 28 as by bolts 30 to prevent accidental displacement of the distributing pipe 21. Auxiliary plates 31 are carried by the main plates 45 27 and are connected thereto by ribs 32, the auxiliary plates 31 being adjacently positioned and adapted to engage opposite sides of the same water tube 26, disposed between the tubes 26 that support the upper ends 50 of the cooperating plates 27. From an inspection of Fig. 3 it will be observed that the cleaning fluid agent issuing radially from the distributing pipe 21 will first engage the main plate 27 and be diverted in 55 an oblique path through the unobstructed spaces between the tubes. By this form of shield the cleaning fluid is prevented from coming in direct contact with the nearest portion of the tube 25 directly positioned 60 beneath the same as is shown in Fig. 3 and serious damage to the tubes at this point is prevented.

I have shown numerous methods of accomplishing this result, and another form is 65 disclosed in Figs. 5 and 6 wherein the main

plates 27 carry upstanding lugs 28 and retaining collars 29 similar to the form shown in Figs. 3 and 4, but in this form, the shields are directly clamped to each tube 26 in the upper row. The plates 27 in Fig. 5 have 70 their lower ends directed toward each other as at 33 to be positioned directly beneath the upper tube 26 for supporting the same while a rib 32 connects the lower turned ends 33 of the plates to the modified form of 75 shield 34 as is indicated. The shield 34 is composed of two members of inverted V-shape when assembled on the tube 25, and as shown the adjacent faces of the shield sections 34 are cut-away as at 35 so that the upper ends 36 thereof alone contact. Thus, when the bolts 30 are tightened, the shield sections 34 are caused to bind upon each other and be more securely held in 80 position. With this arrangement, the cleaning fluid jet delivered from the nozzle 24 will strike the apex of the inverted V as is evident and be divided into two streams traveling in oblique paths between the in-turned ends 33 of the plates 27 and the shield 85 members 34. With this arrangement, as in Fig. 3, the tubes 25 in the second row are protected from the cutting force of the cleaning jets, and yet being of such size as to permit a thorough cleaning of the 90 major portions of the tubes.

Another form of the invention is shown in Figs. 7 and 8, and as is illustrated, the cleaning fluid distributing pipe 21 is supported independently of the shields, there being provided a saddle 37 carried by an arm 38 secured to the clamp 39 fixed to one of the tubes 26 in the upper row. The shields are also of slightly different construction, and in this form the means for 100 holding the shields fixed to the water tubes is carried by those portions of the shields engaging the second row of tubes 25. The main plates 27 of the shields terminate at the upper sides of the water tubes 26 and 105 the lower ends thereof are inwardly directed as at 33 and are connected to V-shaped elements 34 by the ribs 32. As clearly shown in Fig. 8, the opposite ends of the V-shaped elements 34 are connected by the transverse 110 bolts 40 and upon tightening the bolts 40, the same are securely fastened to the tubes 25 while the plates 27 are securely bound to the tubes 26.

The simplest form of construction of the 115 device, and another modified form, is shown in Figs. 9 and 10 and in this instance, the saddle 37 for supporting the distributing pipe 21 carries a lug for connection with the clamp 39 which is secured about one of the 120 upper tubes 26. The shields for protecting the tubes in the second row and for dividing the stream delivered from the distributing pipe to cause the same to travel in oblique paths is substantially of the same con- 125 130

struction shown in Figs. 7 and 8, but in these Figs. 9 and 10, the shields are alone supported by the tubes 25, the same being formed of companion members 34 surrounding the upper sides of the tubes 25 and extending to a point below the horizontal transverse axes thereof as at 41, as is clearly shown in section, while the same are retained in position upon the tubes 25 by the bolts 40 passing through the upper sides thereof. The opposed faces of the members 34 in each of Figs. 5, 7 and 9 are similarly constructed so that a better binding and retaining action may be obtained in securing the same upon the tubes.

Still another form of the invention is disclosed in Fig. 13, and as illustrated, the protecting shield is supported on the cleaning fluid distributing pipe 21, the plates 27 of the shields being constructed in a manner to coöperate with the pipe to permit the suspension of the shields. The clamp used in this form is similar to the clamp shown in Fig. 10, the same including a band portion 39 surrounding an upper tube 26 and carrying a seat element 37 forming a journal bearing for the distributing pipe 21. The lower ends of the plates 27 are diverted and are connected to the shield members 34 by the connectors 32, the shield being substantially of inverted V-shape as shown in the other figures; but in this form the apex of the shield has an overlapping joint 34^a which obviates the use of fastening bolts 40 and also insures the joint between the two shield sections against seepage. The upper ends of the plates 27 are arranged substantially parallel as is indicated and each upper end is bifurcated to provide a pair of legs 42 that are adapted to straddle the distributing pipe 21 while a bridge piece 43 connects the upper ends of the legs 42 and rests upon the pipe 21 to form a bearing or support for the plates 27. It will therefore be seen that in the operation of the device, the distributing pipe 21 is revolved in the bearings 37 and although the shields are supported by the bridge pieces 43 upon the pipe 21, relative movement of the shields and pipe is prevented by the relative positions of the different parts of the device.

From the above detailed description of the invention, it is thought that the construction and operation thereof will be readily apparent, it being noted that this invention was designed to prevent unnecessary damage, as erosion, to those portions of the water tubes lying adjacent the discharge orifices of the distributing pipes, as well as permitting a distributing pipe having a direct radial discharge orifice to be used and divide or divert the cleaning fluid jets issued radially therefrom and thereby cause the same to travel in oblique paths. Also, while the nozzles shown in Figs. 3 and 5 are in

staggered relation, and those in Figs. 7 and 9 are in alinement, it is to be understood that any desired combination and disposition of the nozzles on the distributing pipes may be provided without departing from the spirit 70 and scope of the invention as set forth in the following claims.

What I claim as new is:—

1. In a soot cleaner for water tube boilers, the combination of a revolvably mounted 75 cleaning fluid distributing pipe having radial outlet openings, the jets from each opening adapted to discharge in planes at right angles to the longitudinal axis of the pipe, means for supporting the pipe above 80 the tubes of the boiler, and means below and spaced from the pipe for protecting the tubes and deflecting the jets of cleaning fluid from the openings into the passages between the tubes. 85

2. In a soot cleaner for water tube boilers, the combination of a revolvably mounted cleaning fluid distributing pipe having radial outlet openings, and means for supporting the pipe above the tubes of the 90 boiler, the said means constituting shields arranged to overlie all of the tubes of at least two rows adjacent to said distributing pipe to receive the jets of cleaning fluid and deflect the same from direct contact 95 with said tubes.

3. In a soot cleaner for water tube boilers, the combination of a cleaning fluid distributing pipe adapted to be mounted over the tubes of a boiler and having radial outlet openings adapted to project a cleaning fluid between the tubes of the top row, and means adapted to overlie the tubes of the next row in line with the pipe openings for protecting the tubes and deflecting the jets 100 into the passages between the tubes. 105

4. A soot cleaner for water tube boilers including a revolvably-mounted cleaning fluid distributing pipe having discharge orifices in alinement with boiler tubes, and 110 means for diverting the flow of cleaning fluid issuing from said orifices, the said means comprising a plurality of elements, each element being formed of a pair of similar members detachably connected together. 115

5. A soot cleaner for water tube boilers including a revolvably-mounted cleaning fluid distributing pipe having discharge orifices in alinement with boiler tubes, and means for diverting the flow of cleaning 120 fluid issuing from said orifices, the said means being positively secured to chosen boiler tubes and loosely resting upon others, and including vertical and inverted V-shaped members. 125

6. A soot cleaner for water tube boilers including a revolvably-mounted cleaning fluid distributing pipe having discharge orifices in alinement with boiler tubes, and means for diverting the flow of cleaning 130

- 4
- fluid issuing from said orifices, the said means comprising a plurality of elements each being formed of similar members, with each member engaging different tubes.
- 5 7. A soot cleaner for water tube boilers including a revolvably-mounted cleaning fluid distributing pipe having discharge orifices in alinement with boiler tubes, and means for diverting the flow of cleaning
- 10 fluid issuing from said orifices, the said means comprising a plurality of elements, each being formed of members engaging at least three different tubes, and connecting means between the members of each element.
- 15 8. In combination with a water tube boiler, and a cleaning fluid distributing pipe arranged therein, of a plurality of shields carried by the tubes, each shield comprising a pair of identically formed members having portions resting upon an upper tube and a pair of tubes of the second row, each member further carrying an element extending upwardly into engagement with another tube in the upper row.
9. A soot cleaner comprising in combination with a boiler having water tubes therein, a cleaning fluid distributing pipe arranged in said boiler above said tubes, and shields supported by the boiler tubes and carrying bearings for the distributing pipe, each shield comprising a pair of main plates clamped together above the upper row of tubes and extending to and in engagement with the second row of boiler tubes, auxiliary plates in engagement with the upper row of tubes, and connectors between the main and auxiliary plates. 25
- 30
10. A boiler-tube cleaner, comprising jet-forming means for directing a rotatable jet of steam toward a diagonal interval between rows of boiler tubes, and means for deflecting the jet to retain it in the diagonal interval between the rows of tubes, said jet-directing means comprising a nozzle whose axis generates a plane surface. 40
- 45
- In testimony whereof I affix my signature.
- FREDERICK W. LINAKER.
